UNITED STATES PATENT OFFICE.

CHARLES P. FINDLEY, OF HUNTINGTON BEACH, CALIFORNIA, ASSIGNOR OF ONE HALF TO LORRAINE M. FREEMAN, OF RIVERSIDE, CALIFORNIA.

SAND LIFTER.

Application filed October 5, 1923. Serial No. 666,761.

To all whom it may concern:

Be it known that I, CHARLES P. FINDLEY, a citizen of the United States, residing at Huntington Beach, in the county of Orange 5 and State of California, have invented new and useful Improvements in Sand Lifters, of which the following is a specification.

My present invention being referred to as a sand lifter, it should be understood that 10 this invention is directed primarily to the handling of liquids containing solids in suspension, such as the oils obtainable in numerous wells which tend to become "sand-ed up" after a longer or shorter period of 15 use; and my invention comprises also a system or method of handling sand-contaminated oils or other liquids containing heavy solids in suspension.

Although there are now on the market 20 and in use a number of pumps that will handle oils containing a comparatively high percentage of sand, especially in the case of comparatively deep wells there is a tendency for the sand to settle back, during the 25 ascent of the oil, with the result that the pump and adjacent parts soon become choked in a manner which prevents further operations; and it is accordingly an object of this invention to provide means associated 30 with a pump or sucker rod, and preferably attached to the joints thereof although movable relatively thereto, for keeping the sand and oil thoroughly admixed and causing the sand to advance upward with the oil, my 35 preferred means for the purpose referred to comprising a pair of oppositely disposed pivoted members capable of occupying either substantially vertical positions, during the downward movement of a pump rod, 40 or substantially horizontal positions, during the rise thereof, these being preferably secured by a pair of hinged pins to a pair of small and substantially flat plates, which may correspond in diameter to the diameter 45 of the squared head commonly provided adjacent the end of a section of oil well pump or sucker rod, it being possible to secure one of my lifters in its position of use by the mere longitudinal movement of a pivot pin, 50 and a preferred construction being such as to permit each lifter so assembled to move up and down through a limited distance upon, and during the corresponding vertical movement of, a sucker rod.

Other objects of my invention will appear 55 from the following description of a preferred embodiment thereof, and from the appended claims, taken in connection with the accompanying drawings, in which:

Fig. 1 is a vertical section showing how 60 my sand lifting units may be associated with the sucker rod of a deep well pump.

Fig. 2 is a similar view of a single lifting unit and associated parts, on an enlarged 65 scale, showing the relative positions occupied during a lifting movement.

Fig. 3 is a similar view showing the relative positions of parts during the descending movement.

Fig. 4 is a plan view of a single lifting 70 unit of the same general character. The drop-limiting means indicated in Fig. 3 are slightly different from the type shown in the remaining figures.

Referring to the details of that specific 75 embodiment of my invention chosen for purposes of illustration, 1 being a sectional sucker rod adapted to reciprocate a plunger 2, of the type currently employed in deep oil wells, or of any preferred type, and 3 being a tubing through which the pumped oil may be delivered at the top of a well, a lateral outlet opening being indicated at 4, at the top of the well, and additional strings of tubing or casing being suggested 80 at 5 and 6, my sand lifting units S are shown as applied to the squared portions 7 adjacent the upper ends of the respective sections 8 of the sucker rod 1; and although various alternative constructions might al- 85 ternately be employed, I prefer to form my respective sand lifters from suitably shaped portions of sheet metal secured together by pivot or hinge pins, each unit preferably comprising a pair of oppositely disposed relatively movable wing elements 9, 9', secured by substantially parallel pins 10, 10', to a pair of interposed plates 11, 11', the described construction being in various respects preferable to a three-piece construction, one of its advantages being the fact that, by the organization referred to, assembling is facilitated, it being possible to insert one of the pivot pins 10, 10' in advance, finally inserting the other of these 105 pins at the moment when the respective sections of sucker rod are being lowered with in a well tubing, or the like.

In order to permit the wing sections of initiating the upward movement of oil or my lifting unit to rise into substantially the sand, or a mixture thereof. position suggested in Fig. 3 during the descent of a sucker rod and thereafter assume, during the elevation of said rod, substantially the horizontal position shown in Fig. 2, any suitable means may be provided; but I consider it advantageous to provide, for this purpose, the substantially horizontal extensions 12, 12'; shown as integral with the interposed plates 11, 11', although slightly offset relatively thereto; and it is an advantage of the construction above described that, although the motion of my lifting plates relatively to a sucker rod is restricted, each lifting unit is nevertheless free to play end down upon the squared section to which it may be secured; it being understood that the organization referred to is designed and adapted to maintain a substantially uniform mixture of oil and sand, or the like, throughout an extensive vertical column, the agitation effected by my respective sand lifters, which optionally are pivoted in planes alternatively at right angles to one another, being effective to prevent or retard the subsidence of sand or the like, during the elevation of a column of liquid with which it may be associated; and my described sand lifting means may be employed in conjunction with any preferred type of pump or means for

Although the type of drop-limiting means shown in Figs. 2 and 4, may effectively contribute to the agitation of an oil, the alternative form shown in Fig. 3 may be deemed preferable in certain cases as diminishing the friction of my sand lifter during the descent of the sucker rod by which they are carried.

Although I have herein described one complete embodiment of my invention, it will be understood that various features thereof might be independently employed, and also that various modifications might be made without a departure from the spirit and scope of my invention as the same is indicated above and in the following claim.

What I claim is:

In a sand lifter, the combination with a sucker rod coupling having a square neck of a pair of plates fitting against opposite sides of the square neck, wings fitting against the other opposite sides of the square neck and hingedly connected to the plates and adapted to swing upwardly and not downwardly.

In testimony whereof I have signed my name to this specification.

CHARLES P. FINDLEY.
